UNITED STATES PATENT OFFICE

2,464,000

LOUVER MECHANISM FOR ATTIC
VENTILATION

August W. Schild, Houston, Tex.

Application February 12, 1946, Serial No. 647,100

3 Claims. (Cl. 98—43)

1

This invention relates to a noiseless automatic Venetian grille or louver construction for attic ventilation or the like.

The primary object of the invention is to provide a novel hinge mounting for the grille slats to render them noiseless in opening and closing under the action of a ventilating fan.

Other objects are to provide means to adjustably limit opening of the grille slats to prevent them from opening past dead center and to facilitate closing thereof when the fan is not operating, and to provide means to counterbalance the grille slats to prevent them from closing fast and making excessive noise.

This invention is illustrated in the accompanying drawings, wherein:

Fig. 1 is a vertical section showing the grille installed for ventilation of an attic.

Fig. 2 is an enlarged fragmentary plan view of the grille.

Fig. 3 is a vertical section of the grille open.

Fig. 4 is a vertical section of the grille closed.

Fig. 5 is a section on the line 5—5 of Fig. 3, and

Fig. 6 is a plan of the structure shown in Fig. 5.

Referring to the drawings in detail, 10 designates a frame which is shown as rectangular and installed in an attic ceiling 11, above which is the attic space 12. The ceiling joists 13 support a housing 14 over the ceiling opening 15, said housing having a suction chamber 16, a fan chamber 17 in which a ventilating fan is adapted to be installed, a reinforcing frame 18, and an outlet opening 19.

The grille comprises a plurality of spaced parallel grille slats or shutter blades 20 which extend across the frame from side to side. These slats or blades are hinged to the frame sides and to a central frame bar 27 by tape hinges 22. Bars 21, which constitute governor bars, connect the blades at and intermediate their ends so that the latter will open and close together. The blades 20 are attached to the bars 21 by strands 26 which are passed or looped around the bars 21 in side grooves or notches 23 of the latter, tied at the top as indicated at 24, and anchored by staples or other suitable fasteners 25 to the bars 21. These strands are passed through the tapes 22, which tapes are looped around the blades or slats 20 of the louvers and secured to the frame to hinge the slats to the frame sides and to the frame bar 27. The tapes 22 are fastened to the frame sides and to the frame bar 27 in any suitable manner, preferably by fastening the overlapping ends of the doubled or looped tapes 22

2

to the frame sides and to the frame bar 27 by nails 28 or the like, so as to permit the slats or blades 20 to move freely up and down to open and closed position without noise. The blades 20 overlap when closed, thus closing the ventilating opening and avoiding the necessity of using a screen beneath the opening and blades of the louver.

A counterbalancing spring S is connected at 10 one end to the central bar 21 by a rod 29 and hook 30, and at the other end to an upright post 31 fixed on the end of the frame 10 away from which the louver blades or slats close. A screw 32 is threaded into the end of the central bar 21 adjacent the post 31 and is adapted to contact said post 31 to limit opening of the louver blades 20 so as to prevent them from passing dead center and to thereby insure closing thereof by gravity against the action or tension of the relatively weak spring 28 and under the weight of the bars 21. The spring 28 assists the opening of the grille blades under the action of the fan suction and prevents the shutter blades from closing too fast, thereby eliminating noise or rattle from flapping of the blades open and closed, as is the case when usual metal hinges are employed.

What I claim is:

1. A noiselessly operable louver structure comprising, a frame having therein an opening for flow of air therethrough, a set of gravity closed slats extending across said frame and over said opening, hinge means connecting said slats to said frame for opening and closing movements of said slats relative to each other to control flow of air through said opening, said hinge means comprising loops of flexible material extending around said slats and brought together and fastened to said frame adjacent to one edge of each slat, whereby the inherent flexibility of the material from which said loops are formed provides for noiseless swinging movements of said slats between open and closed positions relative to each other, and means to limit opening swinging movements of said slats.

2. A noiselessly operable louver structure comprising, a frame having therein an opening for flow of air therethrough, a set of gravity closed slats extending across said frame and over said opening, hinge means connecting said slats to said frame for opening and closing movements of said slats relative to each other to control flow of air through said opening, said hinge means comprising loops of flexible material extending around said slats and brought together and fastened to

said frame adjacent to one edge of each slat, whereby the inherent flexibility of the material from which said loops are formed provides for noiseless swinging movements of said slats between open and closed positions relative to each other, a bar extending transversely relative to and across said slats, means cooperating with said bar to limit opening movements of said slats, and strands passing through said loops adjacent to the free edges of said slats and extending around and fastened to said bar, whereby said slats are connected together to swing simultaneously.

3. A louver structure as set forth in claim 2 including a post extending substantially perpendicularly from the frame, a counterbalance spring connecting the bar with said post, and a screw carried by said bar for engagement with said post to limit opening movements of the slats.

AUGUST W. SCHILD.
